UNITED STATES PATENT OFFICE.

GUSTUS A. OTT, OF BUCYRUS, OHIO.

STRAINER.

1,283,278.

Specification of Letters Patent. Patented Oct. 29, 1918.

Application filed June 3, 1918. Serial No. 238,000.

To all whom it may concern:

Be it known that I, GUSTUS A. OTT, a citizen of the United States, residing at Bucyrus, in the county of Crawford and State of Ohio, have invented a new and useful 5 Strainer, of which the following is a specification.

This invention relates to strainers for use in connection with down spouts or conductor 10 pipes, etc., especially where connected to cisterns, one of the objects of the invention being to provide a device of this character which can be attached readily to a down spout and can be quickly adjusted to direct water 15 either into a cistern connected to the device, or to an overflow drain, there being means for straining the water when conducted in either direction.

Another object is to provide a device of 20 this character which can be cleaned readily of all accumulated material on the separating screen.

A still further object is to provide means whereby the strainer can be thawed out, 25 should water freeze therein.

With the foregoing and other objects in view which will appear as the description proceeds, the invention consists of certain 30 novel details of construction and combinations of parts which will be hereinafter more fully described and pointed out in the claims, it being understood that various changes may be made in the construction and arrangement of parts without departing from the 35 spirit of the invention as set forth in the appended claims.

In the accompanying drawings the preferred form of the invention has been shown.

In said drawings

40 Figure 1 is a front elevation of the device. Fig. 2 is a central vertical section therethrough, the down spout, guide pipe, and operating means being shown in elevation.

45 Fig. 3 is a section on line 3—3, Fig. 2. Referring to the figures by characters of reference, 1 designates a casing, preferably 50 rectangular, as shown, and provided in its bottom with a central outlet opening 2 extending from front to rear thereof, while at each side of this central opening and extending partly across the bottom, is an outlet opening having a sleeve 3 extending therefrom, said openings being indicated at 4 and 5 respectively. One of the sleeves is 55 adapted to be connected to a cistern while

the other is to be connected to an overflow drain. An inclined spout 6 is extended forwardly and downwardly from the back end of the central opening 2 and has side flanges as shown at 7. This spout serves to direct 60 solid matter forwardly from the filter after it has been separated from the water, as hereinafter explained.

Flanges 8 extend upwardly from the sides of the opening 2 and located close to and parallel with the upper edges of the flanges are supporting rods 9. Segmental plates 10 are fitted in the casing 1 against the front and back walls thereof, the lower or small ends of the plates being so shaped as to project into the space between the flanges 8 and to rest on the rods 9. Screens 11 connect the edges of the opposed plates 10 and diverge upwardly, the lower ends of the screens forming aprons 12 adapted to extend over 70 and between the flanges 8.

The casing 1 has a removable cover 13 provided with a central stationary sleeve 14 having a slot 15 extending half way therearound, there being notches 16 in the lower 80 edge of the slot at the ends thereof. Mounted for rotation in this sleeve is a tube 17 the upper end of which terminates below the upper end of the sleeve 14 while its lower end forms an elbow located between the upper ends of the screens. A pin 18 is extended radially from this tube 17 and through the slot 15 and serves to hold the tube and sleeve assembled and also as a means whereby the tube can be rotated 90 through 180° so as to discharge through the elbow against either screen 11. When the pin 18 is at either limit of its movement it rests within the adjacent notch 16.

The upper end of the sleeve 14 is turned 95 as at 19 to form a seat for a tubular coupling section 20 which projects loosely into the tube 17 and has a spout 20' extending from the wall thereof into which hot water may be poured when it is desired to thaw 100 ice formed within the screening device. The down spout or conductor pipe 21 is to be connected to the section 20.

It is thought that the operation of the device will be obvious. When the cistern is 105 to be filled the tube 17 is rotated to one extreme position so as to direct water against the screen 11 overhanging the opening 4 or 5 opening into the cistern. After the cistern has been filled the tube can be rotated 110

to its other extreme position and the water will thus be directed against the other screen and pass out into the overflow drain. The solids removed from the water by the 5 screens will gravitate through the central opening 2 and along the spout 6. When it is desired to clean the device, the cover 13 is removed and the segmental plates 10 and screens 11 can be lifted out of the casing.

10. What is claimed is:-

1. The combination with a casing having a central outlet for solids and side outlets for water through its bottom, of screens overhanging the water outlets and converging to the central outlet, and means for directing water against either of the screens.
2. The combination with a casing having a central outlet for solids and side outlets for water through its bottom, of downwardly converging screens overhanging the respective water outlets and leading to the central outlet, and adjustable means between the screens for directing water against either of the screens.
25. 3. The combination with a casing having an outlet at the center thereof for solids and side outlets for water through its bottom, of

connected screens removably mounted in the casing and overhanging the respective water outlets, said screens converging downwardly 30 to the central outlet, a water conducting tube extending into the casing and between the screens and having an elbow at the lower end thereof, and means for rotating the tube to direct the elbow toward either of the 35 screens.

4. The combination with a casing and downwardly converging screens within the casing, there being outlets below the respective screens and between said screens, of a 40 removable cover, a conducting tube revolvable in the cover and having an elbow at the lower end thereof and between the screens, means for rotating the tube to extend the elbow toward either screen, and 45 means for holding the tube in either of said positions.

In testimony that I claim the foregoing as my own, I have hereto affixed my signature in the presence of two witnesses,

GUSTUS A. OTT.
